TIRE

Frank M. Mitch, Akron, Ohio, assignor to The
B. F. Goodrich Company, New York, N.Y., a corporation of New York

Filed June 16, 1967, Ser. No. 7,498

Term of patent 14 years

(Cl. D90—20)

The figure is a perspective view of a tire showing my new design.

The dominant features of the design reside in those portions shown in full lines.

I claim:

The ornamental design for a tire, substantially as shown and described.
